UNITED STATES PATENT OFFICE.

TERRY B. GORDON, OF JAMAICA PLAIN, MASSACHUSETTS.

DESIGN FOR A GAME-BOARD.

51,203.

Specification for Design. Patented Aug. 28, 1917.

Application filed January 6, 1917. Serial No. 141,039. Term of patent 7 years.

To all whom it may concern:

Be it known that I, TERRY B. GORDON, a citizen of the United States, residing at Jamaica Plain, in the county of Suffolk and State of Massachusetts, have invented a new, original, and ornamental Design for a Game-Board, of which the following is a specification, reference being had to the accompanying drawings, forming part thereof.

The figure is a plan view of "a game-board," showing my new design.

I claim:

The ornamental design for "a game-board," as shown.

TERRY B. GORDON.

Witness:

HARRY C. DAGGETT.
